HOLDER WITH FEEDING ARRANGEMENT FOR THE POSITIVE ELECTRODE OF A
SEARCHLIGHT

Application filed June 27, 1928, Serial No. 288,785, and in Germany June 29, 1927.

The present invention relates to a holder for the positive electrode of a searchlight, where the electrode is continuously rotated—as for instance is the case in the so-called Becklamp—and where the holder is provided with an arrangement by which the positive electrode when in operation is moved forward at times so as to ensure the arc to be invariably in the focal point of the collecting system of the searchlight.

According to the invention the arrangement destined to feed and to revolve the positive electrode is constructed as follows:

Near the front (burning) end of the electrode clamps are provided, capable of rotating about the electrode axis, the clamps connected with simultaneously revolving rods, running in the direction from the front (burning) end towards the rear, by the aid of which rods the clamps are pressed upon the electrode from the rear and moved forward together with same. In this way one obtains an electrode feeding device which can be made very simple, permitting the feeding device to grip the electrode at a point comparatively near its front end. An advantage is thereby derived in that the electrodes may be consumed except for a particularly small remainder.

The annexed drawing shows a constructional example of the holding device according to the present invention.

Fig. 1 of the drawing represents a plan of the device, partly drawn in a section and partly in a side view, Fig. 2 a section on the line 2—2 of Fig. 1, Fig. 3 a diagrammatic view of the arrangement effecting the forward motion of the repeatedly mentioned rods, Fig. 4 a diagrammatic view of a switch, and Fig. 5 a section on the line 5—5 of Fig. 1.

In an angle piece *a*, which is intended to be fixed within the searchlight and the upper end of which is constructed as a bearing, a sleeve *b*, having a flange constructed as a bevel gear *c*, is rotatably disposed. This bevel gear cooperates with a second bevel gear *d* supported on the shaft of a motor *d*. The motor *d* is attached to the angle piece *a*. The sleeve *b* is screwed together with a second sleeve *e* carrying four rods *f*. These rods

are provided with oblong recesses into which catches *e*¹, which are attached to sleeve *e*, engage, so that rods *f* are taken along when sleeve *e* rotates. The rods, furthermore, are fixed in a way permitting their being shifted lengthways. By means of the springs *g*, which are fastened to the sleeve *e* on one side and to the rods *f* on the other and which lie in the recesses *f*² of the rods *f*, the rods (as seen in Fig. 1) invariably are drawn towards the right. On the left-hand side (as seen in Fig. 1) the rods *f* are provided with recesses *f*³ in which there are fixed short levers *h* capable of rotating about pivots *h*¹. To the outer ends of these levers there are hinged rods *i* which also are capable of being shifted lengthways in sleeve *e*. At the right hand end the rods *f* have been shaped as handles, *f*⁴, passing through and protruding out of sleeve *e* where the rods *i* are provided with a small pin *i*¹ to prevent them from slipping too far into sleeve *e*. To the inner ends of the levers *h* diamonds *h*² are attached. Sleeve *e* is intended to take an electrode *k*⁰. Each of the levers *h* represents a clamp to hold the electrode the front (burning) end of which comes to lie near the levers. If, for instance, the rods *f* retain their position, and if the rods *i* be shifted forward, the points of the diamonds will grip into the electrode, thus clamping same between the levers. The back end of each of the rods *f* has a pin *p* screwed in. Opposite the rear ends of these rods *f* a body *j* is fixed to freely rotate on sleeve *e*. Opposite the rods *i* this body is bounded by two helical surfaces *j*¹ and *j*² and opposite the pin *p* by oblique surfaces *o*. The way the helical surfaces *j*¹, *j*² and the surfaces *o* are arranged is shown in Figures 3 and 5. In Fig. 3 the arrangement of these surfaces is illustrated. The body *j* carries a spur gear *j*³ which forms the one crown wheel of a returning planet gear the second crown gear of which is represented by a spur gear *k* firmly connected to sleeve *e* and of somewhat smaller diameter than wheel *j*³. The planet wheels of this gear are formed by two spur gears *k*¹ and *k*² which are mounted on one and the same shaft and which are supported in a toothed wheel *k*³ freely rotatable on sleeve *e*. Op-

100

posite this pinion a latch l^1 movable about axle l is provided for on a bracket a^1 . By means of a spring l^2 the latch is held in the position as shown in drawing, where it does not engage the toothed wheel k^3 . The latch l also is connected to a rod m carrying a core iron m^1 at its lower end. The core iron immerses into a solenoid m^2 connected in series to a source of current n and to a selenium cell n^1 (cf. Fig. 4). Cell n^1 is attached laterally in the casing of the searchlight. Between the cell and the arc an optical system n^2 is provided for projecting an image of the arc, whereby an arrangement is made permitting this image to appear at a point next to the light-entering aperture of the cell so long as the arc lies within the focal point of the reflector, and to enter the light-entrance aperture of the cell whenever a change occurs in the position of the arc as is the result of the consumption of the positive electrode. At the front end of sleeve e there finally is fitted a disc q the crosswise hatched part of which consists of quartz and the remainder of metal. A brush q^1 , sliding on this disc, is attached to the casing of the motor d and serves to convey the current to the electrode which latter is connected to sleeve e by means of plate springs s .

The device shown is operated in the following manner. Bevel gear c together with sleeve e and the spur gear k , as well as rods f with the pins p and the rods i are rotated by means of motor d . Thereby the rods f with the levers h , and—when the electrode k inserted—also the rods i will be drawn by springs g to the rear until the rods i lie on the helical surfaces j^1 and j^2 , or the pins p on the slide surfaces o . If then the latch l^1 is not engaging the toothed wheel k^3 , i. e., if the arc of the lamp lies within the focal point of the searchlight reflector, the rods i and pins p will shift forward the slide surfaces j^1 , j^2 and o , thus taking along wheel j^3 , while the two planet wheels k^1 and k^2 will also revolve, together with the toothed wheel k^3 , about the axis of the crown wheels, whereas they do not rotate about their own axis. Once, however, a certain length of the electrode is consumed and the image of the arc projected by lens n^2 falling into the light-entering aperture of selenium cell n^1 , the resistance of cell n^1 will reduce, making a comparatively strong current flow through the solenoid m^2 . As a result, the latter attracts the core iron m^1 , bringing the latch l^1 to engage the toothed wheel k^3 and thus prevents further rotation of same. With the aid of the planet wheels k^1 and k^2 the rotation of wheel k is then conveyed to wheel j^3 , which—having a greater diameter than wheel k , as previously mentioned—rotates somewhat slower than wheel k , and, consequently, remains somewhat behind of the rods f and with the pins p , and the rods i , whereby body

j is caused to rotate relatively to the rods in the direction of the arrow shown in Figures 3 and 5. The following occurs if then the position of the rods is such as illustrated in the drawing: The two rods i in the middle of the helical surfaces j^1 and j^2 are moved forward, viz. in the direction of the burning end of the electrode k^0 , and thus not only cause the diamond points of the two corresponding levers h to be pressed into the electrode, but at the same time a gradual movement forward of the electrode together with the two corresponding levers h and rods f , and this even contrary to the action of the springs g . During this time the corresponding pins p are not in touch with the surface of the body j but at a certain distance. In the drawing the two other rods i are shown to just have reached the ends of the helical surfaces j^1 and j^2 , and, if turned a little more, they would glide off quite suddenly, thus giving way to the tension of the respective springs g which, as mentioned above, tend to draw the rods f in backward direction. This sudden pull is, however, avoided by the pins p and the slide surfaces o , for, as soon as one of the rods i leaves the end of the helical surface, the respective pin p comes into touch with one of the slide surfaces o and is caused to glide downwards on the same, which means that the backward movement of the appertaining rod f can take place only in accordance with the said gliding in downward direction. In this manner the electrode is moved forward by always at least two rods i , which are opposite to one another, and is latched at intervals until the arc lies within the focal point of the reflector. As may be seen in the arrangement as represented in the drawings, there always are at least two rods i occupying a position in which the respective levers h either grip the electrode or move it forward.

I claim:

1. In a holding device for the positive electrode of a searchlight, a holder for the electrode, rotatable about the axis of the electrode, a motor running continuously in the same direction, means for coupling the holder to the said motor, a number of clamps fixed to the said holder near the front end of the electrode, a number of rods extending from the clamps towards the rear end of the holder, the rods being attached to the holder and capable of being shifted in the direction of said axis, and means for shifting these rods in the direction of said axis, the rods, when moved, being adapted to tighten or loosen the said clamps and to move them in the direction of said axis.

2. In a holding device for the positive electrode of a searchlight, a holder for the electrode, rotatable about the axis of the electrode, a motor running continuously in the same direction, means for coupling the hold-

- er to the said motor, a number of clamps fixed to the said holder near the front end of the electrode, a number of rods extending from the clamps towards the rear end of the holder, the rods being attached to the holder and capable of being shifted in the direction of said axis, a body disposed in the device at the rear end of the said holder and capable of rotating about the said axis, this body containing helical surfaces lying opposite the rear ends of these rods and coacting with them, and means for rotating this body relatively to the holder about the said axis, the rods being adapted—when moved by turning the said body—to tighten or loosen the said clamps and to move them in the direction of said axis.
3. In a holding device for the positive electrode of a searchlight, a holder for the electrode, rotatable about the axis of the electrode, a motor running continuously in the same direction, means for coupling the holder to the said motor, a number of clamps fixed to the said holder near the front end of the electrode, a number of rods extending from the clamps towards the rear end of the holder, the rods being attached to the holder and capable of being shifted in the direction of said axis, a body disposed in the device at the rear end of the said holder and capable of rotating about the said axis, this body containing helical surfaces lying opposite the rear ends of these rods and coacting with them, a pinion connected to the said holder, another pinion of different diameter connected to the said body, and two additional pinions one each of which engages one of the aforesaid two pinions, and supported on a shaft which lies parallel to the said axis and is capable of being rotated about same, and means for locking the said shaft, the rods being adapted—when moved by turning the said body—to tighten or loosen the said clamps and to move them in the direction of said axis.
4. In a holding device for the positive electrode of a searchlight, a holder for the electrode, rotatable about the axis of the electrode, a motor running continuously in the same direction, means for coupling the holder to the said motor, a number of clamps fixed to the said holder near the front end of the electrode, a number of rods extending from the clamps towards the rear end of the holder, the rods being attached to the holder and capable of being shifted in the direction of said axis, a body disposed in the device at the rear end of the said holder and capable of rotating about the said axis, this body containing helical surfaces lying opposite the rear ends of these rods and coacting with them, a pinion connected to the said holder, another pinion of different diameter connected to the said body, and two additional pinions one each of which engages one of the aforesaid two pinions, and supported on a shaft which lies parallel to the said axis, a toothed
- wheel capable of rotating about the said axis, the said shaft being rotatably supported in this toothed wheel, a latch disposed in the device and adapted to engage the toothed wheel, and means for controlling this latch, the rods being adapted—when moved by turning the said body—to tighten or loosen the said clamps and to move them in the direction of said axis.
5. In a holding device for the positive electrode of a searchlight, a holder for the electrode, rotatable about the axis of the electrode, a motor running continuously in the same direction, means for coupling the holder to the said motor, a number of clamps fixed to the said holder near the front end of the electrode, a number of rods extending from the clamps towards the rear end of the holder, the rod being attached to the holder and capable of being shifted in the direction of said axis, and means for shifting forward part of these rods in the direction of said axis, and for drawing back the remaining ones and vice versa, the rods being adapted—when moved—to tighten or loosen the said clamps and move them in the direction of said axis.
6. In a holding device for the positive electrode of a searchlight, a holder for the electrode, rotatable about the axis of the electrode, a motor running continuously in the same direction, means for coupling the holder to the said motor, a number of levers lying in radial planes and facing the said axis, the said levers being adapted to lie against the said electrode with their inner ends, a number of rods supported by the said holder and capable of being shifted in the direction of said axis, the said levers being mounted in swing-out fashion at the front end of these rods, a like number of other rods—capable of shifting in the direction of the axis—being mounted on the holder, the said levers being floatingly connected with their outer ends to the second named rods, and means for displacing the latter rods in the direction of the said axis.
7. In a holding device according to claim 6 a number of springs connected to the rods named in first place adapted to draw them back.
8. In a holding device for the positive electrode of a searchlight, a holder for the electrode, rotatable about the axis of the electrode, a motor running continuously in the same direction, means for coupling the holder to the said motor, a number of levers lying in radial planes and facing the said axis, and which are adapted to lie against the said electrode with their inner ends, a number of rods supported by the said holder and capable of being shifted in the direction of said axis, the said levers being mounted in swing-out fashion at the front end of these rods, a number of springs connected to these rods and adapted to draw them back, a like num-

ber of other rods—capable of shifting in the direction of the axis—being mounted on the holder, the said levers being floatingly connected with their outer ends to the rods named in the second place, a body at the rear end of the said holder and capable of rotating about the said axis, this body containing helical surfaces lying opposite the rear ends of the rods named in the second place and 10 coacting with them, and means for rotating this body relatively to the holder about the said axis.

9. In a holding device according to claim 8, the said body being equipped with inclined slide surfaces lying opposite the rear 15 ends of the first named rods and coacting with them.

10. In a holding device for the positive electrode of a searchlight, a holder for the 20 electrode, rotatable about the axis of the electrode, a motor running continuously in the same direction, means for coupling the holder to the said motor, a number of levers lying in radial planes and facing the said axis, the 25 said levers being adapted to lie against the said electrode with their inner ends, an even number of rods supported by the said holder and capable of being shifted in the direction of said axis, the said levers being attached 30 in swing-out fashion to the front end of these rods, a like number of other rods mounted on the holder and capable of shifting in the direction of the said axis, the said levers being floatingly connected with their outer ends to 35 the rods named in the second place, a body disposed in the device at the rear end of the said holder and capable of rotating about the said axis, this body containing helical surfaces half in number of the rods named 40 in the second place, the helical surfaces lying opposite the rear ends of these rods and coacting with them, the said body being equipped with inclined slide surfaces same in number as the helical surfaces, these sliding-surfaces lying opposite the rear end of 45 the first-named rods and coacting with them, and a number of springs connected with the first named rods and adapted to hold the rear ends of the latter in contact with the said slide surfaces.

50 11. In a holding device according to claim 6 a number of springs connected to the first-named rods and adapted to draw them back, each of the first-named rods being equipped 55 with a handle in order to allow them to be displaced contrary to the action of the springs.

12. In a holding device according to claim 6 each of the said levers being at its inner 60 end equipped with a diamond point.

FRANZ MEYER.
